UNITED STATES PATENT OFFICE.

WILLIAM B. GARRISON, OF WASHINGTON, DISTRICT OF COLUMBIA.

DESIGN FOR A FAN.

42,623.

Specification for Design.

Patented June 18, 1912.

Application filed April 20, 1912. Serial No. 692,131. Term of patent 3½ years.

To all whom it may concern:

Be it known that I, WILLIAM B. GARRISON, a citizen of the United States, residing at Washington, in the District of Columbia (whose post-office address is No. 1225 Pennsylvania avenue northwest, in said city,) have invented a new, original, and ornamental Design for Fans, of which the following is a specification, reference being had to the accompanying drawing, forming part thereof.

The figure is a face view of a fan, showing my new design.

I claim:

The ornamental design for a fan, as shown.

WILLIAM B. GARRISON.

Witnesses:

C. C. HINES,
W. E. DENNIS.
